UNITED STATES PATENT OFFICE.

JOHN O. HUFFMAN AND EMIL J. LAUFFER, OF CLEVELAND, OHIO, ASSIGNEES, BY
MESNE ASSIGNMENTS, TO THE WHITE SEWING MACHINE COMPANY, OF CLEVE-
LAND, OHIO, A CORPORATION OF OHIO.

TENSION DEVICE FOR SEWING-MACHINES.

1,167,823.

Specification of Letters Patent. Patented Jan. 11, 1916.

Application filed January 30, 1913. Serial No. 745,078.

To all whom it may concern:

Be it known that we, JOHN O. HUFFMAN and EMIL J. LAUFFER, citizens of the United States, and residents of Cleveland, in the county of Cuyahoga and State of Ohio, have invented a certain new and useful Improvement in Tension Devices for Sewing-Machines, of which the following is a full, clear, and exact description.

10 The invention relates to the sort of tension devices which are employed for putting the desired tension on the upper thread of a sewing machine.

The tension device shown in the drawing, 15 in which the present invention is embodied, is constructed with special reference to attaining certain desirable qualities which are due wholly or partly to said invention. For example, the tension device is a self contained piece of mechanism, the parts of 20 which may be assembled and adjusted, apart from the machine, and then this piece of mechanism may be secured to the machine head in working relation to the parts thereof. Moreover, this tension device is so 25 constructed as to make it easy to quickly put the thread between the tension disks where it belongs, and to practically prevent the thread from going anywhere else and so 30 becoming tangled in any other part of said device. Additionally, the construction is such that the tension on the thread may not only be increased and diminished, but may 35 with certainty be restored to a given condition, which, for example, was found to be satisfactory upon a certain piece of work.

In the drawing, Figure 1 is a sectional side elevation of a tension device embodying the invention, and the adjacent parts of the 40 sewing machine head to which it is removably secured. Fig. 2 is a side elevation of said tension device. Both of these figures are double size. Fig. 3 is a rear view of the 45 said tension device apart from the machine head. Fig. 4 is a side elevation of the device with the indicator disk and finger piece removed. Fig. 5 is a front view of the 50 tension release plate. Fig. 6 is a side view of the stud. Fig. 7 is a front view of the indicator plate; and Fig. 8 is a front view of the tension spring; and Fig. 9 is an end view of the split friction sleeve.

Referring to the parts by letters. T represents a part of the machine head. The front

plate *t* is the part to which the tension device is removably secured, so as to project at its rear end through a hole *t*¹. S represents the needle bar; Q the presser bar; R the presser bar lifter; and U the tension release lever. The above mentioned parts are old either in the form shown or in some equivalent form. The lever U is of bell crank form, and one arm is extended to a point where the presser bar lifter will operate it at the same time that it lifts the presser bar.

The tension device includes as its main frame member a thin metal base plate A adapted to be laid flat against and then connected by screws 2 with the machine head. A tubular stud B is fixed to said plate and extends through the same, projecting both in front of and behind it. The projecting rear part of this stud serves to support and anchor the thread take up spring D, by means which will be presently described.

One tension disk C lies against and is fixed to said back plate, and the stud B passes centrally through it. The movable tension disk C¹ embraces the stud in front of the fixed disk. These two disks are substantially dish shaped,—their middle portions being bent away from each other so as to leave a recess between them when their opposed faces engage. In this recess between the disks a thread sheave F is placed, which sheave loosely embraces and is freely rotatable upon the stud. Outside of the movable tension disk C¹ is the tension release plate D. This not only embraces the stud, but it has a bar *d* which passes through and is movable in a longitudinal diametrical slot *b* in said stud. Outside of this plate and engaging with it is the tension spring E. This is in the form of a thin metal disk which loosely embraces the stud B and has a plurality of rearwardly bent arms *e* which engage the tension release plate. Outside of this spring the tension nut G screws onto the threaded front end of stud B and into engagement with the tension spring so as to apply to it the proper tension which will be transmitted through the tension release plate D to the movable disk C¹. A cup shaped indicator disk H is clamped to this tension nut. It has a rearwardly projecting annular flange *h* which extends rearwardly far enough to make it substantially impossible to get the thread anywhere in

the device except between the two tension disks C, C¹ where it belongs. On the front face of this disk H are indicator graduations 0 to 8, inclusive, which are intended 5 to be read in connection with a pointer J which is fixed to the back plate and extends over the indicator disk. On this indicator disk are two outwardly projecting lugs h² which, by engaging with this pointer, bring 10 the indicator disk to a standstill. That is to say, they limit the possible turning of the disk to a trifle less than one complete revolution. In order to fasten this indicator disk to the tension nut a finger piece 15 K is utilized. This slips somewhat tightly over the front end of the tension nut; and when sufficiently pushed back will clamp the indicator disk between itself and an annular shoulder g on the nut. A screw k 20 which screws radially through this finger piece engages the little beveled flange g on the tension nut, wherefore when this screw is screwed in the finger piece is pulled rearward so as to clamp the tension disk, 25 as stated. When the parts are assembled, and before the indicator disk is clamped to the tension nut, this nut is screwed on until the two tension disks are pressed toward each other with the desired minimum ten- 30 sion. Then the indicator disk is placed in such relation to the pointer as to indicate zero. Then this indicator disk is clamped to the tension nut by the finger piece and its screw. Now, when it is desired to apply 35 more tension, the tension nut and disk are turned so as to screw the nut onto the stud B. If, the user of the machine is using it on thin goods and finds that the tension is right for this work, when the indicator disk 40 reads 3, for example, this can be remembered. The tension may then be changed for other work, but when the operator begins to work upon the same class of thin goods, it is easy to restore the tension de- 45 vice to the condition found to be best for that particular use.

In the tubular stud and projecting rearward therefrom is a tension release pin M, the front end of which engages the cross 50 bar d on the tension release plate D. The rear end of this pin M is engaged and moved forward by lever when the latter is operated as before described. By this forward movement of the said pin M the tension release plate is moved forward so as to relieve 55 the pressure tending to force the tension disk C¹ toward the fixed disk C.

Associated with all efficient tension devices is a very light thread take up spring. 60 Such a spring N is shown in the drawing as a part of this device. There is a long tubular coil N of fine spring wire which terminates in the hook shaped arm n which is extended into the path of the thread as it 65 passes out from between the tension disks.

This coil of wire embraces a split cylinder P which fits friction tight upon the projecting rear end of the stud B. This split cylinder has two arms p, p¹, one of which engages with a loop on the rear end of the 70 spring coil and anchors it. The other end extends to a position where it may be conveniently reached by means of a tool such as a screw driver, through a hole in the side of the head. With this tool the operator may turn this split cylinder upon the projecting rear end of the stud and so wind up or unwind the spring coil, and thereby apply greater or less tension to the thread 75 take up spring arm. 80

Having described our invention, we claim:

1. In an upper thread tension device for sewing machines, the combination of a fixed stud adapted to be secured to the sewing 85 machine head, and to project forwardly therefrom, said stud being externally threaded at its front end, a fixed tension disk, and a movable tension disk,—both of which embrace said stud and have opposed 90 annular surfaces which are in contact and have their marginal edges curved away from each other, a spring acting to press the movable tension disk against the fixed tension disk with greater or less force, a 95 tension nut which screws onto said stud against said spring to vary the tension of said spring, and an annular indicator disk which is centrally fixed to said nut and has a rearwardly extended cylindrical marginal 100 flange,—the rear edge of which is extended rearwardly past the plane in which lies the front edge of the movable tension disk.

2. In an upper thread tension device for sewing machines, the combination of a fixed stud adapted to be secured to the sewing machine head and to project forwardly therefrom, said stud being externally threaded at its front end, a fixed tension disk, and a movable tension disk,—both of 105 which embrace said stud and have opposed annular surfaces which are in contact and have their marginal edges curved away from each other, a spring acting to press the movable tension disk against the fixed 110 tension disk with greater or less force, a tension nut which screws onto said stud against said spring to vary the tension of said spring, and an annular indicator disk which is centrally fixed to said nut and has a rearwardly extended cylindrical marginal 115 flange,—the rear edge of which is extended rearwardly past the plane in which lies the front edge of the movable tension disk, 120 and a fixed pointer for coöperation with said indicator disk.

3. In an upper thread tension device for sewing machines, the combination of a fixed stud adapted to be secured to the sewing machine head, and to project forwardly 125 130

therefrom, said stud being externally threaded at its front end, a fixed tension disk, and a movable tension disk,—both of which embrace said stud and have opposed annular surfaces which are in contact and have their marginal edges curved away from each other, a spring acting to press the movable tension disk against the fixed tension disk with greater or less force, a 10 tension nut which screws onto said stud against said spring to vary the tension of said spring, and an annular indicator disk which is centrally fixed to said nut and has a rearwardly extended cylindrical marginal flange,—the rear edge of which is extended 15 rearwardly past the plane in which lies the front edge of the movable tension disk, a pointer, and two stops carried by said indicator disk for engagement with opposite sides of said pointer to limit the turning 20 movement of said indicator disk.

In testimony whereof, we hereunto affix our signatures in the presence of two witnesses.

JOHN O. HUFFMAN.
EMIL J. LAUFFER.
